UNITED STATES PATENT OFFICE.

CHARLES B. WEBSTER, OF FALL RIVER, MASSACHUSETTS, ASSIGNOR OF
ONE-HALF TO JAMES K. LANNING, OF BOSTON, MASSACHUSETTS.

LOOM-SHUTTLE.

No. 797,477.

Specification of Letters Patent.

Patented Aug. 15, 1905.

Application filed December 1, 1904. Serial No. 234,993.

To all whom it may concern:

Be it known that I, CHARLES B. WEBSTER, a citizen of the United States, residing at Fall River, in the county of Bristol and State of Massachusetts, have invented an Improvement in Loom-Shuttles, of which the following description, in connection with the accompanying drawings, is a specification, like letters on the drawings representing like parts.

My invention consists in new and useful improvements in loom-shuttles, and particularly in "hand-threading" shuttles wherein the filling-thread is guided by the hand of the weaver into the delivery-eye of the shuttle.

My invention consists not only in improvements by which the construction of such shuttles is materially simplified and improved, but also in the provision of means whereby the threaded filling-thread is prevented from detaching or entangling entrance into the open threading-slot at either end thereof.

In the drawings, Figure 1 shows in plan the head or forward end of a shuttle embodying one form of my invention, the threaded position of the yarn being shown in full lines and a position reached during threading being shown in dotted lines. Fig. 2 shows a similar view in side elevation. Fig. 3 is a sectional plan taken on the line 3 3 in Fig. 2. Fig. 4 is a vertical transverse section taken on the line 4 4 in Fig. 1 and looking toward the forward end of the shuttle. Fig. 5 is a similar section taken on the line 5 5 in Fig. 1 and looking toward the rear of the shuttle. Figs. 6, 7, and 8 are details showing the thread-guide in front, side, and rear elevation, respectively.

My invention is concerned with the construction and relation of the thread-guiding passages and may be applied to any ordinary or usual form of shuttle, such as the one here shown, which has the usual shuttle-body *a*, the spindle-recess *b*, and the spindle *s*.

Leading forward from the spindle-recess *b* is a longitudinal thread-guiding passage *c* of any suitable shape, but preferably round, and, as here shown, having a flaring mouth and being substantially coaxial with the spindle. This longitudinal passage leads to and connects with a transverse passage *d*, the latter being cut into the shuttle-head through the shuttle side, from which the thread is delivered. The passage *d* is of a suitable shape, preferably, as herein, of a generally circular

cross-section, to receive the preferably metallic thread-guide *e*. This thread-guide *e* may have any suitable shape; but in the illustrated embodiment of my invention shown it comprises the cylindrical shank *e'*, herein solid, and the guiding portion *e''*, herein bored to provide a thread-guiding passage *e''*. The passage *e''* terminates in a flared mouth at the outer beveled face *e'* of the guiding portion *e''*, and the thread is permitted entrance to the passage through the slit *e''* near the bottom of the guide. At the rear of the guiding portion *e''* the guide *e''* is cut away to form a lateral notch or recess, which communicates with the bore *e'* and the slit *e''*, and the shell-like face which overhangs between the slit and the recess is beveled upward and backward and the corner thereof rounded to form the guiding-heel *e'*, so that a thread, if drawn downward and over the said heel, will be naturally and easily drawn into the thread-guiding passage. The thread-guide is forced into the passage *d* until the shank *e'* seats itself at the end of said passage, the proportions of the parts being such that the upper part of the beveled face is then about flush with the side walls of the shuttle. A projecting lip *e''* is preferably formed upon some part of the thread-guide, and the passage *d* is cut away to correspond thereto, such lip serving to locate and position the guide when inserted. When in position, the lateral recess *e''* upon the thread-guide alines with the longitudinal passage *c*, which latter is preferably slightly above the axis of the thread-guide, and the thread when threaded passes through the said passage down and against the recess *e''* and then through and out of the lateral thread-guiding passage *e''*, as shown in full lines in Fig. 1.

For the purpose of quickly and manually guiding the thread to the passage *e''* I have provided open thread-entering slots or passages as follows: A vertical arc-shaped slit *f* is cut in the top of the shuttle-head and sweeps from a point at *f'*, Fig. 1, over and above the location of the thread-guide recess *e''* and over the longitudinal passage *c*, terminating above the flaring mouth of the latter and so related to its mouth, Fig. 4, as to approach it in a tangent to form an overhanging guarding-lip *f''*, the object of which will be referred to. This vertical slit can be formed by a single cut of a cylindrical saw and is the only slit or passage necessary for the top of the shuttle,

although I have herein shown a rectangular hole g , which may be cut, if desired, for inspection of the thread-guide. Connection between the vertical slit f and the transverse passage d is formed by a single horizontal slit h , (see Fig. 2,) which is preferably in or about the plane of the axis of the passage c . The overhanging wall e^9 at one side of the slit e^5 is preferably of a lesser radius than the wall on the opposite side of said slit, so that when the thread-guide is seated in the passage d a connecting-passage i is formed between the wall e^9 and the body of the shuttle, such passage connecting the horizontal slot h and the thread-entering slit e^5 . This overhanging wall is flattened opposite the slit h , but curves downwardly and toward the slit e^5 . When the shuttle is to be threaded, the thread is drawn into the inner end of the vertical open threading-slot f downward until it reaches the horizontal slot h , backward to the thread-guide e^9 , and then downward and into the slit e^5 . The disposition of the passages is such that this is accomplished by what is practically a single movement of the hand. For the moment the thread is drawn across the face e^9 of the thread-guide the continued tension upon it slips it down over the heel e^7 and forces it into the thread-guiding passage e^3 and into the position shown in full lines in Fig. 1. When threaded, the yarn is prevented from reentering the open threading-slot at any point. At the delivery-eye of the shuttle the beveling of the outer face of the thread-guide causes the shuttle-wall to project relatively beyond the exposed mouth of the thread-entering slot e^5 , and the normal draft of the thread therefore maintains the latter out of the mouth of such slot. This result is further assisted by the fact that the thread is caused to pass over the elevated guiding-wall e^{10} of the guide and is thereby maintained above and away from the mouth of such slot throughout its length. At the entering end of the thread-guiding passage the thread is also maintained out of the open threading-slot f , (see Fig. 4,) for the convolutions of the thread as they leave the bobbin do so in left-handed rotation, and the outgoing strand thereof when it deviates from an axial line does so by gyrating about the axis of the spindle in a left-handed direction, passing over but never under the lip f^2 .

The "ballooning" of the thread—that is to say, the too rapid unwinding and release from the bobbin of the successive spiral convolutions of the yarn—is responsible for much of the dethreading and trouble with hand-threading shuttles. With my shuttle the dethreading-entrance of the thread into the open threading-passage at its entrance end from ballooning or any other cause is prevented.

The shuttle herein described is extremely simple in its manufacture, the wooden body of the shuttle having been utilized to the greatest possible degree, but in a very simple man-

ner, to form the thread-entering and thread-guiding passages. The thread-guide may be cast of metal, if desired, and the shuttle prepared for its reception in substantially four operations only—namely, the boring of the longitudinal passage c of the transverse passage d , cutting the saw-slit f , and then the slit h . Although the lip e^9 may be wholly relied upon to position the guide, the pin p may also be inserted, if desired. The finished shuttle presents no irregularities in contour, and although having an open thread-entering slot substantially all the exposed portion thereof is comprised in the narrow continuous slit f and the similar shorter slit h .

I have herein shown for illustrative purposes one form of my invention. It is to be understood, however, that my invention is in no wise limited to the details thereof, but that the same may be embodied in many different forms without departing from the spirit thereof.

I claim—

1. A hand-threading shuttle having a thread-guiding passage leading from the spindle-recess, said passage being substantially circular in cross-section and cut in the body of the shuttle, and an open threading-slot leading to said passage, the inner exposed mouth thereof being substantially tangential to the exposed mouth of said thread-guiding passage and forming thereby an overhanging lip in the body of the shuttle.

2. A hand-threading shuttle having an unbushed thread-guiding passage leading from the spindle-recess, an open threading-slot leading to said passage, and means for preventing the entrance of the threaded yarn into said open threading-slot.

3. A hand-threading shuttle having a passage of cylindrical bore leading from the spindle-recess and a slot leading from the top of the shuttle-head to said passage, and cut cross-wise the latter.

4. A hand-threading shuttle having longitudinal and transverse thread-guiding passages, a vertical slot leading from the spindle-recess to the outer shuttle-face and a horizontal slot leading from said slot to said transverse thread-guiding passage.

5. A hand-threading shuttle provided with an unbushed longitudinal thread-passage, and a transverse thread-passage, the latter provided with a thread-guide and a vertical thread-entering slot leading from the spindle-recess to the right face of the shuttle.

6. A hand-threading shuttle provided with longitudinal and transverse thread-guiding passages and an arc-shaped slot leading thereto from the upper face of the shuttle.

7. A thread-guide for a loom-shuttle having a thread-guiding passage, a beveled face, a thread-entering slit and a thread-guiding wall located to maintain the thread out of the mouth of said slit.

8. A thread-guide for a loom-shuttle having a thread-guiding passage and a slit leading thereto, a lateral recess, said guide having a flat outer wall portion curving to and toward said slit and said lateral recess.

9. A thread-guide for a loom-shuttle having a bore, a slit leading to the bore, a lateral recess also leading to the bore, and a guiding-heel between the slit and the recess.

10. A hand-threading shuttle having a thread-guiding passage leading from the spindle-recess to the side of the shuttle, and a threading-slot leading from the outer surface of the shuttle to said thread-guiding passage; thread-guiding means at the exterior end of said thread-guiding passage for preventing the threads from beginning to reenter said thread-guiding passage; and a guiding-hole being formed at the interior end of said thread-guiding passage from the wooden body of the shuttle and substantially coincident with the linear extension of the spindle, the said threading-slot intersecting said guiding-hole in a substantially tangential manner and in a direction opposed to the unwinding movement of the yarn on the spindle.

11. A thread-guiding piece for hand-thread-

ing shuttles, said piece being substantially cylindrical in general form and having a beveled outer end, with a central, thread-guiding passage leading to one end thereof; a threading-slot cut from the outer surface and communicating with the said thread-guiding passage; and a holding or positioning shank extending in a direction opposite to said thread-guiding passage.

12. A thread-guiding piece for a hand-threading shuttle substantially cylindrical in general form with a central thread-guiding passage leading to one end thereof, a threading-slot cut from the outer surface and connecting with the said thread-guiding passage, and a holding or positioning shank extending in a direction opposite to said thread-guiding passage and a projecting lip to position said guide.

In testimony whereof I have signed my name to this specification in the presence of two subscribing witnesses.

CHARLES B. WEBSTER.
